UNITED STATES PATENT OFFICE

PETER JUUL, OF CHICAGO, ILLINOIS, ASSIGNOR TO LATHAM MACHINERY COMPANY, A CORPORATION OF ILLINOIS

PERFORATING MACHINE

Application filed February 16, 1931. Serial No. 515,919.

The present invention relates generally to perforating machines, but more particularly to a type of perforating machine known as the fanfold perforating machine.

One of the objects of the present invention is to provide a novel and improved construction of a removable head for fanfold perforating machines in which the head and the bed, which carry respectively the punches and the die, may be secured together so that both may be mounted on or removed from the main frame of the machine as a unit.

A further object of the invention is to provide a novel and improved form of perforating machine, in which the head and the bed may be securely locked together so as to prevent any disalignment from the punches with respect to the die, carried by the head and the bed respectively, so as to prevent any injury or distortion of these parts.

A still further object of the invention is to provide a novel and improved perforating device in which the head and the bed may be locked together by certain of the driving parts before the removal from the base or main frame of the machine.

These and other objects are accomplished by providing a construction and an arrangement of the various parts in the manner hereinafter described and particularly pointed out in the appended claims.

Referring to the drawings.

Fig. 1 is a side elevational view of a fragmentary portion of a perforating machine, showing my improved construction of a removable head and bed embodied therein with the operative parts thereof connected in their normal operative position for the purpose of perforating paper or other material;

Fig. 2 is a similar view in which the head and bed are locked together as a unit and are slightly removed from the main frame and operating parts disconnected from the driving parts of the perforating machine;

Fig. 3 is a cross-sectional view taken on the line 3—3 in Fig. 1;

Fig. 4 is an end elevational view of the head and bed connected up in the manner shown in Fig. 1; and

Fig. 5 is an enlarged perspective view of

the driving rod sleeve which also forms part of the locking means for locking the head to the bed; and

Fig. 6 is a perspective view of the clamping and locking block.

In fanfold perforating machines which have heretofore been constructed, considerable difficulty has been experienced in maintaining the punches carried by the head in proper alignment with the perforated dies carried by the bed, and especially in those types of machines in which the head and bed is separately removable from the machine. Then, too, with this type of machine, considerable time and labor is required as well as many difficulties are encountered in properly realigning the punches of the head with the die of the bed.

It is therefore, one of the primary objects of the present invention to overcome these difficulties and provide a novel and improved construction of a perforator head by means of which the head and the bed are locked together as a unit prior to their removal from the main frame of the machine, so that the punches will maintain their alignment with the perforations in the bed. It will also be seen that any number of these removable units of heads and beds may be adjusted on the machine of the unit before they are operatively connected to the driving connections of the perforating machine.

In illustrating one embodiment of my invention, I have shown the same in connection with the main frame or base only a fragmentary portion of which is shown in Fig. 1 of the drawings and is generally indicated by the reference character 10. Formed integrally with and on the opposite ends of the frame 10 and also arranged on the opposite sides thereof, are outwardly extending dove-tailed projections or guides 11, which slidingly receive complementary dove-tailed grooved portions 12, formed integral with the driving bars 13, which are located on the opposite side of the perforating machine. These reciprocating bars 13 are provided on their opposite ends with driving pitman connections 14 which have their up-

per ends pivotally connected as shown at 15 to the opposite ends of each of the bars 13 and the lower ends operatively connected to cranks for reciprocating the bars 13. The 5 pitmen 14 are driven through the medium of any suitable transmission in the manner well understood in the art. Extending longitudinally throughout the upper surface of each of the reciprocating bars 13 is a substantially 10 inverted T-shaped recess 16 in which is detachably connected my improved construction of driving connection between the reciprocating head and the driving bar 13. This driving connection may also be utilized 15 for positively locking the reciprocating head with its complementary bed, so as to prevent disalignment or injury to the punches or die when they are being removed or adjusted longitudinally of the perforating machine. 20 My improved removable head and bed construction in which part of the operative connections are utilized for locking the head to the bed so that the same is removable as a unit, comprises a bed 17 which has a portion 25 of its lower surface suitably machined as shown at 18, so that the same may be seated on complementary finished portions 19 of the main frame 10 of the perforating machine. The main frame 10 is provided with a laterally extending projection so as to form shoulders 20 on the opposite sides thereof. Mounted on the downwardly extending portions 21 formed on the opposite ends of the bed 17 are adjustable locking blocks 22. The 30 locking blocks 22 are provided with slotted apertures 23 extending transversely thereof, which are adapted to receive bolts 24 which are mounted in threaded engagement with the downwardly extending portions 21 of the bed 17. The innermost portion of these 35 blocks 22 are adapted to engage the shoulders 20 of the main frame 10 for securely locking the bed to the main frame 10.

Secured to the bed 17 by means of cap 40 screws 25 is a die 26 which is provided with a plurality of longitudinally aligned perforations extending vertically therethrough for the accommodation of and cooperation with the punches carried by the head in the manner hereinafter described. Located on the 45 opposite end of the bed 17 and extending upward therefrom are two shafts or guide rods 27 which are secured to the bed by means of pins 28'. Reciprocally mounted on the guide 50 rods or shaft 27 is a reciprocating head generally indicated by the reference character 28. This reciprocating head is provided with two vertically extending bores 29, which reciprocally or slidingly receive the shafts 27 55 in vertically guiding the punches through the cooperating perforations formed in the die 26. Founded in the lower portion of the head 28 and secured by means of screws 30 is a punch holding frame, indicated generally 60 by the reference character 31. Mounted in

the punch-holding frame 31, is a plurality of spaced apart punches or perforating pins 32 which are adapted to cooperate with the perforations in the die 26 for punching the material passing thereunder. Formed integrally with the head 28 and on the outer ends thereof are outwardly extending portions 33 in which are mounted driving rods 34. The upper ends of these rods 34 are mounted in threaded engagement with portions 33 and are secured against removal therefrom by means of lock nuts 35. The lower ends of the driving rods 34 are provided with round heads as shown at 36 and are adapted to be seated in the recesses or sockets 37 formed in the lower end of the driving sleeves generally indicated by the reference character 38. The driving sleeves 38 have vertical bores 39 therein, so as to permit the sleeves 38 to be slidably mounted on the driving rods 34. Formed on the lower portion of the driving sleeve 38 is a non-circular flange generally indicated by the reference character 39'. This flange 39' is larger across one diameter than it is across the other 70 diameter at right angle to the first, as clearly shown in Fig. 3 of the drawings. In other words, the upper surface of the flange as indicated at 40 and 41 is adapted to engage the over-hanging shoulder 42 and 43 respectively of the driving bar 13 formed by the inverted T-shaped recess 16. The narrow portion of the flange 39' as indicated at 44, is of narrower diameter and is capable of being withdrawn from between the inwardly 80 projecting shoulders 45 of the inverted T-shaped recess 16 in the reciprocating bars 13. Secured adjacent to the upper end of the sleeve 38 is a laterally projecting pin 46 which is adapted for engagement with the socket 47 90 formed in the sliding or locking block 22. The sleeve 38 is locked or secured to the lower end of the driving rod 34 by means of a set screw 48, the inner end of which is adapted to engage a conical recess 49 located in the 100 rod 34 as shown in Fig. 1 of the drawings; or the sleeve 38 may be locked in the position as shown in Fig. 2 wherein the pin 46 engages the socket 47 in the block 22, in which case the set screw 48 may be secured so that the 110 inner end thereof engages the conical socket 50 in the driving rod 34.

The operation of my improved removable unit for perforating machines is as follows: Let us assume that the operating parts of 120 both the head and the bed are in the position disclosed in Fig. 1 of the drawings and that the operator is desirous of removing the head and the bed as a unit from the perforating machine. To perform this operation it is 125 necessary to loosen the bolts 24 on the opposite sides of the machine and then by loosening the set screw 48 in each of the sleeves 38, the sleeves may be revolved a quarter of a turn so that the narrow portions 44 of the 130

flanges 39 on the sleeves 38 may pass between the inner portions 45 of the inverted T-shaped slots 16 in each of the reciprocating bars 13. After the sleeves have been released 5 from these slots they may again be revolved and raised to a position so that the pins 46 are in alignment with the sockets 47 in the locking blocks 22. When the sleeves are in this position, the set screws 48 may be tightened 10 so the inner ends thereof engage the conical recesses 50 in each of the driving rods 34, after which the blocks 22 may be moved outwardly so that the pins 46 engage the sockets 47 in the block 22. After this has been accomplished, the bolts 24 may be tightened 15 and the head 28 as well as the bed 17 will be rigidly locked together so that both may be removed as a unit from the main frame 10 of the perforating machine. In Fig. 2 of the drawings, the head 28 and bed 17 are shown partially removed from the main frame 10, illustrating the manner in which the same may be removed or mounted 20 upon the machine. In this connection, it will also be noted that any number of these heads 25 may be positioned on the machine and adjusted longitudinally thereon, so that the desired distance between the perforations in the paper may be secured.

From the above description, it will be readily seen that by utilizing the normal driving parts of the head for rigidly locking the head and the bed together as a unit, so that the same may be removed therefrom as a single 30 part, the danger of having the former become disaligned with respect to the die, is entirely overcome. Then too, it will be observed that this construction permits easy and quick replacement of the head, but simplifies construction and arrangement of 35 parts as to simplify the repair and replacement of the head.

While in the above specification I have described one embodiment in which my invention may assume in practice, it will of course be understood that the same is capable of modification and that modification may be employed without departing from the spirit and scope of the invention as expressed 45 in the following claims:

What I claim as my invention and desire to secure by Letters Patent is:

1. The combination with a perforating machine, of a reciprocating head therefor, a bed for said reciprocating head, and means for locking said head to said bed whereby said head and bed may be removed from said machine as a unit.
2. The combination with a perforating machine, of a reciprocating head therefor, a bed for said reciprocating head, and means forming a part of said perforating machine for locking said head to said bed whereby said head and bed may be removed from said machine as a unit.

3. The combination with a perforating machine, of a reciprocating head therefor, a bed for said reciprocating head, driving connections for said reciprocating head, and means whereby said driving connections may be utilized for locking said bed to said head for removing said bed and head as a unit. 70
4. The combination with a perforating machine, of a reciprocating head therefor, a bed for said reciprocating head, driving connections for said reciprocating head, and means whereby certain parts of said driving connections may be utilized for locking said head to said bed for removing said head and bed as a unit. 75
5. The combination with a perforating machine, of a reciprocating head therefor, a bed for said reciprocating head, driving connections for said reciprocating head, and means for adjusting certain portions of said driving connections whereby said head may be locked to said bed so that said head and bed may be removed from said machine as a unit. 80
6. The combination with a perforating machine, of a reciprocating head therefor, a bed for said reciprocating head, driving connections for said reciprocating head including a reciprocating bar, a driving rod, and means for locking said driving rod to said bed, whereby said head and bed may be locked together so that said head and bed may be removed from said machine as a unit. 90
7. The combination with a perforating machine, of a reciprocating head therefor, a bed for said reciprocating head, driving connections for said reciprocating head including a plurality of reciprocating bars, driving rods operatively connecting said bars with said head and means for locking said rods to said bed whereby said head and bed may be removed as a unit from said machine. 100
8. The combination with a perforating machine, of a reciprocating head therefor, a bed for said reciprocating head, driving connections for said reciprocating head including a plurality of reciprocating bars located on the opposite side of said machine, driving rods connecting said reciprocating bars with the opposite ends of said head an adjustable sleeve carried by each of said driving rods for securely fastening said driving rods to said bed whereby said head and bed may be removed as a unit from said machine. 110
9. The combination with a perforating machine, of a reciprocating head therefor, a bed for said reciprocating head, driving connections for said reciprocating head including a plurality of reciprocating bars mounted on the opposite sides of said machine, driving rods connecting said reciprocating bars with said reciprocating head, adjustable sleeves mounted on said driving rods and connected with said reciprocating bars, and adjustable 120
10. The combination with a perforating machine, of a reciprocating head therefor, a bed for said reciprocating head, driving connections for said reciprocating head including a reciprocating bar, a driving rod, and means for locking said driving rod to said bed, whereby said head and bed may be locked together so that said head and bed may be removed from said machine as a unit. 130

plates carried by said bed and adapted to engage said sleeves for locking said bed and said head whereby said bed and head may be removed as a unit from said machine.

- 5 10. The combination with a perforating machine, of a reciprocating head therefor, a bed for said reciprocating head, driving connections for said reciprocating head, including a plurality of reciprocating bars mounted on said machine, driving rods connecting said reciprocating bars with said head, adjustable sleeves for connecting said driving rods with said reciprocating bars, pins carried by said sleeves and adjustable plates carried by said bed for securing said bed to said machine and for engaging the pins on said sleeves for locking said head to said bed, whereby said head and bed may be removed as a unit from said machine.
- 15 11. The combination with a perforating machine, of a reciprocating head therefor, a bed for said reciprocating head, driving connections for said reciprocating head including a plurality of reciprocating bars located 20 on the opposite sides of said machine, said bars having longitudinal inverted T-shaped slots formed therein, driving rods secured to said head, adjustable sleeves mounted on said driving rods and engageable with the slots 25 in said reciprocating bars, and means formed on said sleeves and engageable with said bed for locking said bed to said head whereby said bed and head may be removed from said machine as a unit.
- 30 35. In testimony whereof I have signed my name to this specification, on this 6th day of February, A. D. 1931.

PETER JUUL.
